[] Term: 14 Years[21] Appl. No.: 744,016[22] Filed: Aug. 12, 1991[52] U.S. Cl. ..... D6/601; D6/596[58] Field of Search D6/601, 595, 596; 5/490, 636*CLAIM

The ornamental design for a pillow with border of sets of superimposed fins, as shown and described.

DESCRIPTION

FIG. 1 is a front elevational view of a pillow with a border of superimposed fins showing my new design; FIG. 2 is a top plan view thereof with side views and a bottom plan view being identical;

FIG. 3 is a fragmentary rear elevational view thereof shown separately for clarity of illustration; and,

FIG. 4 is a fragmentary front elevational view of a set of superimposed fins showing separately for clarity of illustration.
